SHOE-MARKING MACHINE.

1,324,878.

Specification of Letters Patent. Patented Dec. 16, 1919.

Application filed December 13, 1915. Serial No. 67,605.

To all whom it may concern:

Be it known that I, JAMES J. CASEY, a citizen of the United States, residing at Boston, in the county of Suffolk and State 5 of Massachusetts, have invented certain new and useful Improvements in Shoe-Marking Machines, of which the following is a specification.

This invention relates to devices for 10 marking the position of buttons, button holes or of both on sheet material such as leather or cloth.

It is more particularly intended for marking 15 the location of buttons and button holes on the uppers of shoes in the process of manufacture thereof. It may be used for marking the location of the buttons on the button fly, or of the button holes on the button hole fly or it may be used for marking 20 both at the same time in the manner indicated by application for patent filed by me on process for marking shoe uppers July 17, 1913, Ser. No. 779,504, and application for patent filed by me on marking machine 25 for shoe uppers, filed Dec. 19, 1913, Ser. No. 807,691, and issued May 16, 1916, No. 1,183,432.

With my device, I use plurality of spaced 30 marking members, such members being preferably awls, arranged on a curved line.

The principal purpose of my invention is to provide such means for laterally changing or adjusting its curve that the positions of the marking members may be 35 altered or adjusted longitudinally along said line at will. The spaced marking means may be made so that the spaces between the marking members can not be varied, they may be slightly movable longitudinally, or in my preferred construction, I arrange them so that they may be adjusted longitudinally by means independent 40 of the means for changing the lateral curvature. This longitudinal adjusting or spacing means preferably acts simultaneously upon all or substantially all of the marking members, and increases or diminishes the distances between them equally.

This invention is distinguished from that 50 shown in application for patent filed by me Dec. 18, 1915, Serial No. 67,604 for marking machine, from the fact that a flexible strip and the lateral adjustment of marking means through the medium thereof is an

essential feature, while in such other application it is not an essential feature. 55

The lateral adjustment or altering the curve need not be simultaneous for all parts thereof.

I prefer to embody my idea in a device 60 which is removable from a punching machine and I preferably make it invertible so that the button locations of the right shoe may be marked by one face and of the left shoe by the other face. 65

In shoe marking machines, the relative spacing between the buttons or button holes have been made adjustable and simultaneously adjustable, but I can, with my device in its preferred form, not only change the 70 spacing of the buttons but also the curve which they form. This curve differs for different styles of shoes and its length differs for different sizes.

For determining the shape of the curve, 75 I prefer to use a flexible or elastic strip member preferably made of metal and associated therewith marking means which are movable thereby so that by changing the curvature of the strip, the curve of the 80 marking means is also changed. I use a rigid frame which may assume various forms and proximate thereto locate a curved flexible strip member which is curved, let us say, horizontally, in relation to the direction of marking members, such as awls, which are vertically disposed with reference thereto. 85

In the drawings, Figure 1 is a plan view 90 of the preferred form of my invention with the top plate removed. Fig. 2 is an elevation thereof as from the right of Fig. 1. Fig. 3 is a plan view of said device showing a different curve and with part of the top plate broken away. Fig. 4 is a sectional view of Fig. 3 on line 4-4. Fig. 5 is an elevation of a punching machine with which I prefer to use my device. Fig. 6 is a detail plan view of a modified construction. Fig. 7 is a detail thereof. Fig. 8 shows another 100 modification. Fig. 9 is a section of Fig. 8 on line 9-9. Fig. 10 is still another modification and Fig. 11 is a sectional detail thereof on line 11-11.

A represents the preferred form of my device as a whole. 20 is the bottom plate and 21 is the top plate. Both are preferably flat of curved contour and together with a rigid

strip 22, which is also preferably curved, and separating bars 23 and 24 form the frame of my device. As so constructed, the inside or concave side is substantially open.

5 The marking means include a plurality of fingers 30 which are of such thickness at their pivot ends 31 and at their other ends 32 that they are slidable between the top and bottom plates in what is ordinarily a 10 horizontal plane. Their ends 32 project from the concave side of the frame and carry at right angles marking means 33 which project at right angles or vertically therefrom. I prefer to arrange on each 15 finger two awls oppositely disposed so that the device may be used either side up.

Each finger is preferably recessed as shown at 34 and near the end opposite the awls is cut away in such a groove 35 that two oppositely disposed pivotal points are formed.

20 Through these grooves and between the pivotal points, I pass a flexible curved strip 40 upon which the fingers will pivot. When the curve of this flexible strip is changed, 25 the marking means which include the fingers 30 and awls 33 thus associated therewith will be moved thereby and will assume and follow the curve of such strip.

As a means for changing the curvature 30 of the strip member, I provide carriers 41 slidable between the top and bottom plates and each grooved at 42 so as to have two oppositely disposed bearing points one on each side of strip 40. These carriers 41 35 are each bored and threaded to receive the screw shank of a set screw 43 each of which passes through slot 45 in rigid strip 22 which is part of the frame. Each has an annular neck 44 which sets into a slot 45.

40 By turning these set screws 43, the carriers 41 are forced in or out carrying with them flexible strip 40 which moves the fingers pivoted thereon and the marking members carried by the fingers as shown in 45 Fig. 3.

I may use, to get the proper spacing, disks 48 similar to carriers 41 and similarly grooved at 49 between the pivot ends of certain adjoining fingers 30, to keep them 50 properly spaced. I prefer to connect adjoining fingers 30 by means of links 10 which are shown as pivoted near their opposite ends to adjoining fingers, and I prefer that the opposite ends of some of said 55 links should be at different distances from the pivotal points of said adjoining fingers on flexible strip 40. If the links were pivoted at equal distances from such pivotal points, when one finger was moved on its 60 pivot, all the others would move the same distance, but by changing the pivotal distances, I am enabled to so arrange the longitudinal adjustment of the marking means that the distances between adjoining marking 65 members can be simultaneously increased

or decreased equally or unequally whether on a straight line or a curve.

In marking the position of buttons on shoes, the position of the lower button is usually taken as the fixed point. I therefore arrange so that the marking awl for this button shall be attached to the finger at one end, and I prefer to attach to the finger at the other end a handle such as 37 by which the spacing between the spaced marking means including the fingers, links and awls can be conveniently altered and positioned. So arranged, the distance moved by the awl associated with the finger which carries handle 37 will be the greatest distance 70 and the distances moved by the other awls associated with the other fingers will be less successively down to the awl carried by the finger at the other end which will move a very small distance. By means of a pin 26 75 which may be passed through any one of the holes 27 in top plate 21 into a hole 38 in the finger to which handle 37 is attached, I can position the parts and lock them against longitudinal displacement. 80

To assist in taking up loose motion, I may connect certain fingers by tension springs such as 46 and 47.

This device A as a whole may be attached to or associated with any suitable form of 95 punching machine B such as shown in Fig. 5 whereby it may be caused to move up and down in the process of puncturing or otherwise marking the sheet material upon which it is to be used. It may be attached to the 100 plunger 101 of the punching machine by any suitable means preferably of such a character that it can be attached either side up and with the ends in either direction.

I prefer to fix the end blocks 23 and 24 105 somewhat in from the ends of the top and bottom plates thus leaving a channel at each end, and I prefer to arrange the plunger 101 with depending clamp members 102 and 103 from which projecting toward each 110 other are tongues 104 and 105 each of a size to fit snugly into an end channel in either direction. When slipped into place, they can be held there by means of set screws 106 which tighten the clamps 102 and 103. 115

In Fig. 6, I show a construction in which the marking means are carried by fingers 50 connected by links 51. Each finger 50 is bifurcated to straddle a collar 52 which has ears 53 to serve as pivots and is fixed by 120 means of a set screw 54 to a flexible strip member 55 which in this case is shown as a wire.

Each finger 50 is of sufficient thickness near its awl carrying end 56 to slide between 125 top plate 57 and bottom plate 58 and the flexible strip 55 is held in position thereby and by tension springs 59 fixed at one end to 55 and at the other end to bottom plate 58. The means for changing the curve of the 130

strip member are shown as eccentrics 60 each of which has a peripheral groove 61 in which strip member 55 sets. Each eccentric 60 is fixed on a pin 62 which passes through 5 the top and bottom plates, and is revoluble therein and is enlarged at 63 to form a knurled thumb piece for turning. The distances of the corresponding ends of links 51 may be the same from the pivotal points of 10 the fingers, or different as shown, whereby the longitudinal spacing of the marking members may be capable of alteration or not as desired.

In Figs. 8 and 9 I show a construction 15 wherein the rigid frame consists only of a rigid strip member 70 which is preferably curved and the marking means consist of marking members which are shown as awls 71 which project from the top and bottom 20 edges of a flexible strip member 72. Member 72 is proximate rigid strip member 70 and is connected therewith by means of set screws 73. The shank 76 of each of these 25 set screws is threaded and passes through a threaded hole in rigid strip or frame 70. Near its end, each set screw 73 passes through a longitudinal slot 77 in flexible strip 72 and is kept in place therein by suitable collars 75 one on each side. Each set 30 screw will therefore swivel in the flexible strip and deflect it laterally, thus altering its curve, as it is screwed in and out of rigid strip 70. Thereby the curved relation 35 between the marking means 77 which, in this case coincides with the marking members, is also changed.

It will be observed that in this construction, the rigid frame is strip 70, the flexible curved strip 72 is proximate thereto and the 40 marking means associated therewith and movable thereby coincides with the marking members or awls 71.

In Figs. 10 and 11, I show still another 45 modification wherein top plate 80 and bottom plate 81 are separated by rigid curved strips 82 and 83 and have end bars 84 and 85. Laterally slidible between the top and bottom plates are two flexible curved strips 86 and 87 in edgewise relation thereto. Between these flexible strips 86 and 87 are a 50 plurality of awl blocks 88 which are longitudinally slidable. Each block 88 carries preferably two oppositely disposed awls 89 and between adjoining blocks are compression springs 90. The block adjoining end bar 84 is preferably fixed while set screw 91 which passes through end bar 85 bears against the adjoining awl block 88. This set screw, together with springs 90, allows longitudinal spacing adjustment as when it is 55 turned in or out, the movement is transmitted to the slideable awl blocks through the springs 90 in a successively decreasing amount. To permit lateral adjustment or 60 change of the curve, I arrange a plurality of

compression springs 92 between rigid strip 83 and flexible strip 87 and opposed to them, I arrange set screws 93 which pass through rigid strip 82 and bear against flexible strip 86. By screwing in or out these set screws, 70 the curve of the marking means may be changed. The top and bottom plates are preferably provided with relatively wide slots 94 and 95 to allow lateral movement of the awls 89 therein. 75

In this construction, the flexible curved strip is the strip 86 and the other parallel strip 87 co-operates therewith, while the marking means includes the marking members 89, block 88, springs 90, etc. 80

With the construction shown in Figs. 6 and 7 and also with that shown in Figs. 10 and 11, I can alter the curve almost simultaneously by taking a stiff flat pattern such as 100 having the desired curve and 85 pressing it up against the awls as shown in Fig. 6 forcing them altogether to conform to its curve as shown by the dotted lines. I can then lock the awls in position by successively turning the eccentrics 60 or the set 90 screws 93 as the case may be.

In adjusting for different styles and sizes, the lateral adjustment of the curve may be determined by the eye, by a pattern such as 100, or by any other similar means, and after 95 the style of the curve is determined, the spacing between the marking members may then be adjusted to the desired size; or the spacing for the size may be first adjusted and the curve may then be altered for the 100 new style.

In practice, the end of the button curve which will be near the top of the shoe is nearly straight while the lower middle portion has the greatest curvature. It is therefore desirable that the greatest longitudinal adjustment should come from near the end of the straight portion. This arrangement is shown in Figs. 1, 2 and 3.

It will also be observed that the angles 110 made by the different links with the fingers varies according to whether the adjoining curvature is considerable or slight.

I claim:

1. In a shoe marking machine, the combination of a flexible strip member, and a plurality of spaced fingers each pivoted near one end thereon and each having a marking member, with a plurality of spacing links each pivoted near its opposite ends to adjoining fingers the opposite ends of some of said links being at different distances from the pivotal points of said adjoining fingers on the flexible strip. 115

2. In a shoe marking machine, the combination of a flexible curved strip member, and a plurality of spaced fingers each pivoted near one end thereon and each having a marking member near its other end, with a plurality of spacing links each pivoted near 120

125

its opposite ends to adjoining fingers the opposite ends of some of said links being at different distances from the pivotal points of said adjoining fingers on the flexible strip, 5 and means for changing the curvature of said strip member.

3. In a shoe marking machine, the combination of a rigid frame, and a horizontally curved flexible strip member proximate 10 thereto, with a plurality of spaced fingers, a pivot near one end of each finger carried by the flexible strip member in such position that each finger may be movable horizontally and each having a vertically disposed

15 marking member near its other end, with a plurality of spacing links each pivoted near its opposite ends to adjoining fingers the opposite ends of some of said links being at different distances from the pivotal points of said adjoining fingers on the flexible strip, 20 and adjusting means between the rigid frame and the flexible strip for changing the horizontal curvature of the flexible strip member.

25 4. In a shoe marking machine, the combination of a rigid frame which includes top and bottom plates and a rigid strip between them, with a flexible strip member between the top and bottom plates and curved in a 30 plane parallel with such top and bottom plates, a plurality of spaced fingers each so pivoted near one end on the flexible strip member as to be slidable between said top and bottom plates and each having a marking member near its other end disposed at 35 right angles to said plates, said fingers being recessed, a plurality of spacing links each pivoted near its opposite ends to adjoining fingers in the recesses thereof, the opposite

ends of some of said links being at different 40 distances from the pivotal points of said adjoining fingers on the flexible strip, means for locking the finger at one end in adjusted position, and adjusting means between the rigid frame and the flexible strip for changing 45 the curvature of said flexible strip.

5. In a shoe marking machine, the combination of a flexible strip member, with a plurality of spaced fingers each pivoted near one end thereon and each having a marking member near its other end, with a plurality of spacing links each pivoted near its opposite 50 ends to adjoining fingers.

6. In a device of the character described the combination of a reversible detachable 55 frame, with a flexible strip disposed between the top and bottom of the frame, and a plurality of marking means movably connected to and movable with the flexible strip, such marking means projecting in opposite directions beyond the top and bottom of the 60 frame.

7. In a shoe marking machine, the combination of a rigid frame which includes a rigid strip, with a curved flexible strip member located between the top and bottom of such frame and proximate the rigid strip, a plurality of marking means connected to and 65 movable with the flexible strip member and projecting in opposite directions beyond the 70 top and bottom of the frame, and means between the rigid strip and the flexible strip member for changing the curvature of the strip member at a plurality of points.

In testimony whereof I hereto affix my 75 signature.

JAMES J. CASEY.
